FOOD DELIVERY BOX

Michael Curcio, Whitestone, N. Y.

Application June 12, 1952, Serial No. 293,155

2 Claims. (Cl. 232—42)

1

This invention relates to a food delivery box. It is an object of the present invention to provide a door delivery box which can be secured to a door or to a building wall for the purpose of receiving deliveries of mail, packages, milk or other goods or articles and thereby eliminate the need for the person in the home or office going to the door or to be at home or in the office to receive the goods.

It is another object of the invention to provide a delivery box adapted to be attached to a door or a building wall which when not in use may be collapsed and folded to conserve space and yet when expanded is adapted to receive large articles.

It is another object of the invention to provide a delivery box adapted to be attached to a door or a building wall with a foldable bottom piece which serves when in a raised position to hold the latch catch retracted and away from the latch projection on the door in the front of the delivery box whereby the box door on the front of the delivery box will be left free to be opened and at the same time the bottom piece serves to cover the opening for the box door and wherein automatically as the bottom of the box is lowered the latch catch is elevated by a spring arm so that the latch projection on the door can engage with the catch and wherein the raising of the door serves to expand the parts of the delivery box and to provide the space for receiving the articles.

Other objects of the invention are to provide a delivery box, having the above objects in mind, which is of simple construction, inexpensive to manufacture, has a minimum number of parts, easy to install upon the door or building wall, collapsible and foldable to consume little space when not in use, efficient in operation and convenient to use.

For other objects and for a better understanding of the invention reference may be had to the following detailed description taken in connection with the accompanying drawing, in which:

Figure 1 is a perspective view of a door having an opening over which the collapsible delivery box of the present invention is mounted;

Fig. 2 is a fragmentary vertical sectional view of the door and of the delivery box in its expanded condition with the door on the delivery box lifted to permit the insertion of goods and the catch raised so that the latch on the door can be engaged thereby, the view being taken generally on line 2—2 of Fig. 1;

Fig. 3 is a sectional view of the door and lock-
55 lifted.

2

ing in top plan of the delivery box shown in full in its collapsed condition with illustration made as to how the same is expanded to prepare the box for the reception of the goods, the view being taken generally on line 3—3 of Fig. 2;

Fig. 4 is a rear perspective view of the delivery box in an expanded condition to receive goods and with portions broken away to show the interior construction thereof;

10 Fig. 5 is a fragmentary vertical sectional view of a portion of the delivery box door and the bottom swung up to the vertical position, the box door being unlocked and lowered, the view being taken on line 5—5 of Fig. 3;

15 Fig. 6 is a fragmentary perspective view of portions of the box showing the manner in which the door acts upon the parts of the box to extend the same as the box door is lifted;

Fig. 7 is a fragmentary vertical sectional view 20 of the box door having its latch engaging the catch, the bottom plate having been lowered, and the box door locked.

Referring now to the figures, 10 represents a 25 door of a household or office having the usual hand knob 11 for retaining the door in the closed position. In the bottom of the door, there is cut a large opening 12 and the delivery box is connected to the inner side of the door over the opening 12.

30 The door opening can be made larger than shown and the front plate attached on the front side of the door and the parts collapsible into and out of the door opening in a manner which will be apparent as the description proceeds.

35 The delivery box has a front plate 13 which is much larger than the opening 12 of the door and through holes 13' of this plate are extended screws 14 which attach the box to the door 10. This front plate 13 has an opening 16 adapted to 40 be filled by a downwardly swingable door 17 having a solid latch projection 19 and a knob 21. The box door 17 is lifted from the opening 12 to the open position as shown in Fig. 2 to permit the insertion therethrough of a milk bottle or other articles in the manner illustrated.

45 On the rear face of the front plate 13 and laterally spaced from one another, are channel members 22 and 23 that are respectively notched to receive hinges 24 and 25. These hinges are connected by fasteners 26 to the rear face of the door. The hinge 24 has an extension 27 and the hinge member 25 has an extension 28. These extensions 28 engage with a back plate 29 to cause its rearward movement as the box door 17 is

Connected to the inner side of a channel member 22 is a long piano type hinge 31 which is in turn connected to a side plate 32. This side plate 32 is connected by a longer piano hinge 33 to another side plate 34 which is connected by another piano hinge 35 to the back plate 29. These hinges and plates 32 and 34 are so arranged that the adjacent edges of the plates with each other and the hinge 33 can be folded inwardly to permit the back plate 29 to be moved forwardly.

The channel member 23 at the opposite side is connected by a hinge 36 to a side plate 31. The side plate 31 is connected by a piano hinge 38 with a side plate 39 which is, in turn, connected by a hinge 40 to the back plate 29. These hinges and the side plates are folded inwardly in the same manner as the hinges and side plates at the other side of the box are folded inwardly so that the back plate 29 is shiftable forwardly and rearwardly with the collapsing or expanding of the side plates. It will now be apparent that with the extensions 27 and 28 engaging the back plate 29 as the box door 17 is lifted the back plate 29 will be moved rearwardly and the box will be expanded.

A bottom piece 41 is hingedly connected along its forward edge by spaced hinges 43 to a supporting member 42 fixed to the inner face of the front plate 13 and along the bottom edge of the opening 16. Spring hinges 44 are connected between the bottom piece 41 and the supporting member 42 which serve to normally lift the bottom piece 41 to a vertical position in front of the opening 16 in the front plate 13. As the box door 17 is lifted and the back plate 29 is moved rearwardly by the hinge extensions 27 and 28, the placing of the milk bottle or other article against and upon the hinged bottom piece will swing down and hold the bottom piece in a horizontal position and supported upon a shoulder piece 45 which is carried by the plate 29.

At the same time that this bottom piece 41 is moved downwardly a catch operating spring arm 46 which is fixed to the under face of the same by screws 47 will engage with recess 48 of a vertically slidable catch 49 and lift the same into a position so that the latch projection 19 can ride over and depress catch 49 to engage the rear face of the same whereby the box lid or door 17 will be held in a locked position as shown in Fig. 7. As long as the bottom piece 41 is in vertical position, the catch 49 will not be engaged by the spring arm 46 nor held in a raised position such that it can be engaged by the latch projection 19 on the door and thereafter the box door 17 will be held free of engagement and so it will not lock. It is only necessary for the delivery man to lift the door and push down the bottom piece 41 and deposit the milk bottle or other articles thereon whereby the catch 49 will be in an operative position so that upon the closing of the box door the same will be locked to prevent access to the delivery box when it is supplied with articles.

Upon removal of the milk bottle from the top of the box and on the inner side of the door, the bottom piece 41 will be automatically lifted by the spring hinges 44 to a vertical position so as to release the box door 17. As this bottom piece is swung up, the catch 49 will be lowered by the spring arm 46 and made free of the latch 19 whereby the door 17 is released. With this ef-

fected, the back plate 29 can be moved inwardly to collapse the side plates. Or if desired, the plates can be separated and the delivery box used for the return of empty bottles. The box is thus conditioned for another delivery of goods thereto. If the box is mounted in a large opening, the parts will be collapsed thereinto and be flush with the rear face of the door or wall.

It should now be apparent that there has been provided a door delivery box which is conditioned when empty to have the door free and permit access thereto and when expanded the box is conditioned to have the box door latched thereto. It should also be apparent that the parts are expanded and collapsed by rearward and forward movement and that the bottom piece keeps the shape of the box when the parts are expanded.

While various changes may be made in the detailed construction of this delivery box, it shall be understood that such changes shall be within the spirit and scope of the present invention as defined by the appended claims:

What is claimed is:

1. A delivery box comprising a front plate having an opening therein, a back plate, horizontally foldable side plate means disposed at the opposite sides of the front and back plates to connect the same together, to permit the expansion and collapse of the box, a bottom piece and means for hingedly connecting the bottom piece to the front plate to permit the same to be swung from a down position upwardly across the opening of the front plate and a box door hingedly connected to the front plate and adapted to close the opening thereof, a latch projection on the door, catch means on the front plate operable by the bottom piece as it is moved down to position the catch means to retain the latch of the door when the bottom piece is in the down position and the door is closed and when the bottom piece is swung up against the front plate to withdraw the catch from the latch so that the door is made free for insertion of articles into the box through the front opening.

2. A delivery box construction comprising a front plate having an opening therein, a back plate spaced from the front plate and side plate means connecting the front and back plates to hold the back plate spaced from the front plate, a bottom piece hingedly connected to the front plate and movable between horizontal and vertical positions, a catch element vertically adjustable on the front plate, a spring arm fixed to the bottom piece and engageable with the catch element to lift the catch element as the bottom piece is moved to the horizontal position and to biasingly retain the catch element in the lifted position, a box door hinged upon the front plate and having a latch projection engageable with the catch element to hold the door in the latched position, the movement of the bottom piece to the vertical position serving to release the box door.

MICHAEL CURCIO.
